UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

VACUUM TUBE CIRCUITS.

Application filed August 19, 1921, Serial No. 493,675, and in France March 5, 1919.

It may often be desirable to supply current to the filament circuits of three-electrode tubes, constituting an amplifying system, through existing commercial power circuits.

5 In view of the fact that the voltage of such power circuits is usually much higher than desirable for filament circuits of vacuum tubes, it would be necessary to connect a resistance in series with the filaments. However, it is 10 well known that the heating of the filaments must be done at a strictly constant voltage. For this reason, the filaments can not satisfactorily be fed directly from an existing direct current power circuit by using merely 15 an ohmic resistance inserted in series with the filaments, because the slightest voltage fluctuations would affect the heating and would cause noises in the receivers of the amplifying apparatus.

20 Instead of the resistance, an inductance coil may be placed in series with the filaments in the heating circuit. However, if this inductance coil must absorb the continuously high voltage the consumption of 25 which was, in accordance with the first suggestion, the function of the resistance, it will be seen that the inductance of this coil assumes a value entirely too large to be practical. This is due to the fact that the inductive 30 reactance of the coil must be larger than the resistance of the winding thereof if a non-fluctuating current is to be supplied to the filaments from the fluctuating direct current source.

35 Even if a resistance unit is placed in series with the inductance coil instead of following the arrangement just described, the size of the inductance coil must still be so great, in order to maintain the large reactance resistance ratio necessary for a non-fluctuating current, that it is uncommercial.

It is the object of the present invention to provide a current feeding arrangement in which the size of this inductance coil is reduced to a practical value. This is accomplished by connecting a resistance unit and an inductance coil in series with the filament or filaments across the power leads and by connecting a resistance in shunt of the inductance and of the filament or filaments.

The single figure of the accompanying drawing represents one embodiment of a cir-

cuit arrangement arranged in accordance with this invention.

The tube 1 comprises the well-known parts: 55 the filament 2, the grid 3 and the plate 4. The filament 2 is fed from the power source 5 through a resistance 6 and an inductance 8, and it is shunted by a resistance 7. The resistance 6 is sufficiently large so 60 that the voltage from the power source is reduced to the proper value for heating the filament of the tube, and the value of the resistance 7 is small with respect to the reactance value of inductance coil 8. By this 65 arrangement the size of the inductance coil 8 is determined, not by the size of the resistance 6 but by that of the resistance 7.

Furthermore, it will be understood that the resistance unit 7 may be variable in the 70 form of a rheostat to control the supply of heating current to the filament.

Having described my invention what I claim is:

1. In combination with a thermionic tube 75 having a filament, a source of direct current for heating said filament, said current source being of substantially higher voltage than necessary for heating said filament and having disturbing fluctuations in voltage, a 80 series circuit connected across said source of direct current, said series circuit including a resistance unit, an inductance unit and said filament, and a resistance unit connected in shunt of said filament and of said inductance 85 unit whereby fluctuations in the current of said filament are reduced.

2. In combination with a thermionic tube having a filament, a source of direct current for heating said filament, said current source 90 being of substantially higher voltage than necessary for heating said filament and having disturbing fluctuations in voltage, a series circuit connected to said current source, said series circuit including a resistance, an 95 inductance and at least one filament, and a second resistance connected in shunt of said inductance and of said filament, said second resistance being small in value with respect to the reactance of said inductance, 100 whereby fluctuations in the current of said filament are reduced.

MARIUS LATOUR.
